UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPETS.

SPECIFICATION forming part of Design No. 12,148, dated February 1, 1881.

Application filed January 7, 1881. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of the elongated octagonal light centers A, ornamented by floral designs; shell - shaped figures C, ornamented by floral designs; curved and scalloped figures D, resembling lace-work, and partly covered by floral designs; scrolls B, diverging from the figures C D, and borders or stripes variously ornamented, arranged about the light centers C and between the figures C and D, as shown.

I claim—

The design for a carpet, substantially as shown and described.

In testimony whereof I have signed my name to this specification in the presence of two subscribing witnesses, this 3d day of January, A. D. 1881.

THOMAS J. STEARNS.
